CATAMENIAL BELT

Flo W. O'Neill, Santa Ana, Calif.

Application September 25, 1937, Serial No. 165,776

1 Claim. (Cl. 128—289)

This invention relates to an improved catamenial appliance, and the present application for patent constitutes a continuation-in-part of and discloses several improvements over and above my 5 invention on a similar device for which application for patent was filed on July 10, 1936, Serial No. 89,942.

One of the important objects of this invention is to provide a more definite and positive means 10 for maintaining the absorbent pad in desired position in the belt while, at the same time, not interfering with the comfort of the wearer in any way.

Other objects include means for providing a 15 sanitary readily cleaned apparatus and one which is light but strong and composed of a minimum of parts.

Another and still further important object of 20 the invention is the provision of special means for retaining the pad in desired position on the support or belt, one such fastening means being a more or less integral part of the belt while the other includes a removable snap-fastened element.

25 A still further improvement disclosed in the present invention is the provision of reinforcing stays in the belt near the ends thereof, the purpose of which is to prevent the belt from twisting and possibly turning upside down in wearing.

30 A still further object is to provide a belt in which fastening means such as pins or the like are eliminated and wherein bunching of the ends of the pads is prevented, and all of which is found quite desirable inasmuch as this belt will, accordingly, lie quite flat and be unobservable through 35 even the thinnest of dresses or similar apparel.

Other and further important objects of the 40 invention will be apparent from the disclosures in the accompanying drawing and following specification.

The invention, in a preferred form, is shown in the drawing and hereinafter more fully described.

In the drawing:

Figure 1 is a perspective view of the improved 45 catamenial belt of this invention, showing an absorbent pad in position thereon.

Figure 2 is a top plan view of the padded portion of the belt, illustrating particularly the novel improvements incorporated therewith.

50 Figure 3 is a longitudinal section of the structure of Figure 2, showing a pad in position on the belt.

Figure 4 is a section on the line 4—4 of Figure 53, looking in the direction indicated by the arrows.

55 Figure 5 is a detail view, parts being broken

away, showing the absorbent pad in position on the belt and illustrating the improved means of fastening the same by fastening clips which grip the gauze wrapping of the pad but do not contact the pad itself.

As shown in the drawing:

The reference numeral 10 indicates generally the belt portion of the improved catamenial appliance of this invention, which belt portion is usually of some elastic fabric and which may or 10 may not be provided with an adjusting means such as a buckle or the like.

Fastened to and depending from the belt portion 10 are front and rear straps or supports 12 and 14 respectively which are preferably of rubberized fabric and are integral with the actual supporting portion 16 of the appliance which is adapted to hold an absorbent pad 18 in proper position with regard to the body of the wearer.

Fastening means for the absorbent pad are 20 provided which, in one instance, are somewhat similar to the fastening means illustrated and described in my previous application hereinabove referred to, the same including snap fastener elements 20 and 20a and 22 and 22a respectively as 25 best shown in Figure 2.

The snap fastener portions 20 and 22 are 30 affixed to the belt portion proper, and the corresponding fastener elements 20a and 22a are affixed to a short length or strip preferably of the same material as the belt as indicated at 24. This strip is attached to the belt by means of a string or cord 26 so as to prevent its being accidentally lost or misplaced.

As best shown in Figure 5, the pad element 28 35 is held in position on the belt structure by fastening the snap fastener or clip elements together through the gauze which forms a part of the wrapping of the pad, thereby maintaining the pad in desired position on the belt while, at the 40 same time, not actually gripping the pad or absorbent portion itself.

The other end of the pad is held in position on the belt by means of a cross strip 30 which is 45 affixed to or is integral with the belt and preferably of the same material, namely, rubberized fabric, and underneath which the pad is simply passed or slipped when it is applied to the belt.

Additionally, the belt is provided with cross 50 braces or stays 32 and 34 respectively which are of some fairly stiff material such as light metal or whalebone or the like, and which act to prevent the belt from twisting or possibly turning upside down during wearing and which, at the 55

same time, are sufficiently disposed toward the ends of the belt so that they will not interfere with the comfort of the wearer in any way.

A unitary binding or edging 36 is provided around the edges of the under-strap element 16, this being for moisture-proofing and supporting purposes.

It will be evident that herein is provided an appliance of the class described which is particularly advantageous in that it provides definite support for the absorbent pad while, at the same time, producing a structure which is practically not noticeable while being worn while it can be put into actual use with a minimum of time and effort.

I am aware that many changes may be made and numerous details of construction varied throughout a wide range without departing from the principles of this invention, and I, therefore, do not purpose limiting the patent granted here-

on otherwise than as necessitated by the prior art.

I claim as my invention:

A catamenial appliance, comprising a main elongated strap of waterproof material for supporting an absorbent pad, cross strips adjacent each end of the strap, said cross strips being fastened at their ends to the edges of the strap and being separated from the strap over their intermediate portions for retaining an absorbent pad there-beneath, one of said cross strips having its ends permanently attached to the strap and the other of said cross strips having its ends removably fastened to the strap, and a cord connected to one end of said removably fastened strap to provide against loss, together with reinforcing cross stays incorporated into the strap at the ends thereof beyond the cross strips, said cross stays being composed of a fairly stiff yet flexible material.

FLO W. O'NEILL. 20
